UNITED STATES PATENT OFFICE.

ROBERT H. VISSER, OF VIRDEN, ILLINOIS.

STARTING-CRANK HOLDER.

Application filed December 13, 1924. Serial No. 755,733.

To all whom it may concern:

Be it known that I, ROBERT H. VISSER, a citizen of the United States, residing at Virden, in the county of Macoupin and State of Illinois, have invented certain new and useful Improvements in Starting-Crank Holders, of which the following is a specification, reference being had to the accompanying drawings.

10 This invention relates to starting crank holders for the starting cranks of automobiles, tractors and the like.

An important object of the invention is to provide a device of this character for securely holding starting cranks of the vehicles in one position thereof to prevent the unpleasant rattling and squeaking noises caused by oscillation and vibration of the crank in its bearing.

20 An important object of the invention is to provide a device of this character, the application of which necessitates no changes whatever in the present structure of the vehicle.

25 A still further object of the invention is to provide a device of this character which will, in event of the breakage of the spring normally employed for holding the starting crank out of engagement with the crank shaft of the engine, securely hold the crank against movement into engagement with the crank shaft.

30 A still further object is to provide a device of this character which may be cheaply and readily produced and as readily installed on the vehicle.

35 These and other objects I attain by the construction shown in the accompanying drawings, wherein for the purpose of illustration is shown a preferred embodiment of my invention and wherein:

40 Figure 1 is a perspective view showing a starting crank holder constructed in accordance with my invention applied to the front end bearing of a vehicle;

Figure 2 is a vertical sectional view therethrough;

Figure 3 is a section on the line 3—3 of Figure 2;

45 Figure 4 is a section on the line 4—4 of Figure 2; and

Figure 5 is a perspective of the latch plate and latch collar removed.

50 Referring now more particularly to the drawings, the numeral 10 generally designates a front end bearing of the crank case

of the engine of the vehicle. This front end bearing receives a bearing 11 formed upon the front end of the crank case which bearing 11 in turn rotatably receives a crank 12 to maintain the same in alignment with the crank shaft 15 of the engine. This crank has secured thereto one end of a spring 14, the opposite end of which bears against the forward end of the bearing 12 to urge the crank forwardly and to withdraw the crank from engagement with the shaft 15 so that the starting head 16 will have its ratchet teeth 17 out of engagement with the starting pin 18 of the crank shaft 15. The starting head of the crank 13 is usually secured in position by a pin (not herein shown) which in accordance with my invention is replaced by a bolt 19.

In accordance with my invention I provide a plate 20 opposing the forward end of the starting head and having an opening 21 formed therein. Upon the starting head by means of the bolt 19 I secure a collar 22 having at its forward edge a projecting latch lug 23 secured to the collar by a reduced neck 24 producing a rearwardly facing latching shoulder 25. Due to the fact that the exterior surface of the starting head 16 is usually unfinished and, therefore, subject to variations in size the collar 22 is split as at 26 so that it may be readily varied in size to fit the starting head. This collar is provided with openings 27 for the passage of the bolt 19. The opening 21 of the plate 20 is of sufficient width to permit the passage therethrough of the latching lug 23 and the neck 24 is of the same width as the thickness of the plate 20.

Pivoted to the plate 20 as at 28 is a latch 29 having a shoulder 30 adapted to engage against the rear face 31. This shoulder 30 is vertically disposed and flatly engages against the rear face 31 of the latch lug 23 when the latch lug has its shoulder 25 fully engaged with the plate 20 at the opening 21 and is normally urged to this position by a spring 32 seated upon an integral extension 33 of the plate 20 and abutting the upper face of the latch. This spring, when the latch is in the last named position, comes into engagement with the upper surface of the plate 20 and is accordingly inoperative to urge the latch further for a purpose presently to appear.

The opening 20 is of slightly greater width

than the extreme width of the latching lug 23 and accordingly by rotating the crank 13, the latching lug 23 will have its rear face 31 forced into engagement with the latch shoulder 30 causing the same to retreat against the action of its spring 32, the entire latch swinging about its pivot until the rear face 31 of the latch is engaged with the edge 34 of the opening 21. At this time if the crank be forced rearwardly, the latch lug will pass through the opening and the entire crank may be moved rearwardly to permit engagement of the starting head with the crank pin 18. The forward end of the latch 23 is reduced in width to a point where it will enter through the opening 21 and between adjacent edges 35 of the opening 21 and that formed by the shoulder 30 of the latch, this reduced end portion being connected with the rear face 31 by an inclined wall 36 operating as a wedging when the crank is moved forwardly to shift the latch 29 about its pivot against the action of its spring 32 and permit the lug to engage in the opening. This inclined shoulder or face forms also a ratchet face preventing sticking of the lug 23 in the opening 21 when the crank is rotated in a clockwise direction as it will be during starting of the engine and will thus prevent the starting crank from being brought to an abrupt stop in event it is forced outwardly by its spring 14 during a cranking operation. The front face 37 of the lug being straight will provide an efficient stop when the crank is being aligned with the opening 21, it being necessary at this time to simply rotate the crank in a counter-clockwise direction and when the lug 23 aligns with the opening 21, the crank will be forced outwardly by the spring 14 and the face 39 of the lug 23 and will engage against the face 35 of the opening 21. The plate 20 must, of course, be secured against movement with relation to the crank case 11 and as a convenient means for securing the plate in such position I provide the plate with integrally formed forwardly extending arms 40, the forward extremities of which are adapted to rest upon the upper surface of the ears 42 of the bearing cap 43 of the bearing 10 and having openings through which the cap bolt 44 may extend.

It will, of course, be obvious that the structure hereinbefore set forth is capable of a considerable range of change and modification without in any manner departing from the spirit of my invention and I accordingly do not limit myself to such specific structure except as hereinafter claimed.

I claim:

1. In combination with a rotatable starting crank for engines, the starting crank being longitudinally shiftable to engage the crank shaft of the engine, a collar secured

to the starting crank and having a latching lug provided with a rearwardly directed shoulder, a plate fixed with relation to the crank shaft and at the opposite side of the collar from the crank shaft, said plate having an opening through which the latching lug of the collar may extend and over one edge of which the shoulder of the latching lug may engage and means carried by the plate yieldably maintaining the latching lug with its shoulder so engaged. 70

2. In combination with a rotatable starting crank for engines, the starting crank being rotatably mounted in a bearing carried by the engine and longitudinally shiftable through said bearing for engagement with the crank shaft of the engine, coacting latch elements carried by the bearing and crank for latching said crank against longitudinal movement and out of engagement with the crank shaft of the engine. 80

3. In combination with a rotatable starting crank for engines, the starting crank being rotatably mounted in a bearing carried by the engine and longitudinally shiftable through said bearing for engagement with the crank shaft of the engine, coacting latch elements carried by the bearing and crank for latching said crank against longitudinal movement and out of engagement with the crank shaft of the engine, including a latching lug carried by the crank, a plate fixed with relation to the bearing and in which the lug is engageable in the forward position of the crank and a yielding element maintaining the latch in engagement in the opening of the plate and from which the latch lug may be disengaged by predetermined operation of the crank. 90

4. In combination with a rotatable starting crank for engines, the starting crank being longitudinally shiftable to engage the crank shaft of the engine, a collar secured to the starting crank and having a latching lug provided with a rearwardly directed shoulder, a plate fixed with relation to the crank and at the opposite side of the collar from the crank shaft, the plate having an opening through which the latching lug of the collar may extend and means carried by the plate and engaging the latching lug when extended through said opening for forcing the latch lug to one side of the opening and thereby engaging said shoulder over one edge of the opening. 105

5. In combination with a rotatable starting crank for engines, the starting crank being longitudinally shiftable to engage the crank shaft of the engine, a collar secured to the starting crank and having a latching lug provided with a rearwardly directed shoulder, a plate fixed with relation to the crank and at the opposite side of the collar from the crank shaft, the plate having an opening through which the latching lug of 110

the collar may extend and means carried by the plate and engaging the latching lug when extended through said opening for forcing the latch lug to one side of the opening and thereby engaging said shoulder over one edge of the opening, said means including a spring pressed latch member yielding

upon a predetermined operation of the crank to permit disengagement of the shoulder from the plate and to thereby permit rear- 10 ward movement and rotation of the crank.

In testimony whereof I hereunto affix my signature.

ROBERT H. VISSER.
